J. W. DAWSON

CLOTHESLINE PROP

Filed Dec. 19, 1923

Inventor:

James W. Dawson,
By dyerupforth, Lee, Chittenden & Wiles
Attest:

UNITED STATES PATENT OFFICE.

JAMES W. DAWSON, OF CHICAGO, ILLINOIS.

CLOTHESLINE PROP.

Application filed December 19, 1923. Serial No. 631,504.

To all whom it may concern:

Be it known that I, JAMES W. DAWSON, a citizen of the United States, residing at Chicago, in the county of Cook and State of Illinois, have invented a new and useful Clothesline Prop, of which the following is a specification.

My invention relates to an improved construction of clothes-line props of the variety in which the pole comprises longitudinally extensible and contractible members; and it is fully described and explained in the specification and illustrated in the accompanying drawing, in which—

15 Figure 1 is an edge view of the complete prop, showing its two members in extended relation for use;

Figure 2 is an enlarged broken perspective view of the same;

20 Figure 3 is a similar view showing a U-shaped sheet-metal band connecting the two relatively slidable members, screwed through its arms to the sides of one member and projecting beyond the face of the latter to an extent adapting the ends to be folded back ear-like over the screw-heads for covering them;

Figure 4 is a section on line 4—4, Fig. 2, showing the ends of the band folded back 30 from the condition in which they are represented in Fig. 3, and

Figures 5 and 6 are sections respectively on line 5—5 and line 6—6, Fig. 2.

The pole-members 7 and 8, which are 35 wooden bars, shown of rectangular cross-section, are formed of relatively soft wood, such as pine; and they are preferably of about the same length. These members are connected flatwise together by means adapting the pole they form to be readily lengthened and shortened for adjusting its length in accordance with requirement for the usual clothes-line propping or other purpose and to be releasably secured together in their adjusted relation. The means I provide for the connecting purpose are the two pairs of sheet-metal bands 9, 10, and the single band 11, the metal of all the bands being preferably galvanized. Two of the bands 9 are 50 applied in spaced relation to the pole-member 8, near the lower end thereof, by causing the arms of each to embrace it, as represented, and form a relatively deep loop 9^a serving the purpose hereinafter described.

55 Two of the bands 10 are applied, in reverse

relation to the bands 9 and with their arms extending over the latter in registration therewith, to the member 7 at some distance below its upper end, to cause their side-arms to embrace it at its edges and overlap those 60 of the respectively cooperating bands 9; and screws 12 (Fig. 5), or the like, are passed through the mutually overlapping arms of the bands 9 and 10 to firmly secure them to the pole-member 8; whereupon the ends of 65 the arms of the bands 10 are bent backwardly to extend them over the heads of the screw-heads to lock the screws in place, and shield their heads against exposure, and particularly to prevent rust thereon from 70 staining the clothes hung on the line that may come into contact with the screw-heads or from becoming entangled with the latter, if they were to become dislodged, as might occur unless prevented by being thus locked 75 by the backwardly-turned ears 10^a formed on the bands 10. The single band 11 is applied to the pole-member 8 to embrace it with its arms near the upper end of the member 7, to the edges of which the arms 80 are secured, as by screws 12 in the manner represented in Fig. 3, whereupon the projecting arm-ends are bent backwardly over the screw-heads to form the shielding ears 11^a (Figs. 2 and 3) for the purposes explained relative to the ears 10^a.

In the band-loops 9^a is confined a reinforcing block 13 of relatively hard wood, such as hard maple, containing a central threaded opening 14 to register with a similar opening 14^a in the member 8, for admitting a handle-forming set-screw 15, of similar hard wood; and on one face of the member 8, near its upper end, is secured a 90 spring clip 16.

The member 8 terminates at its upper end in a screw 17 for enabling a suitable brush, window-cleaner, swab, or the like to adapt the pole to be used for cleaning windows, walls and other objects in elevated 100 position requiring to be reached for the purpose from the ground or floor.

By screwing the handle 15 inwardly to bear its end against the face of the prop-member 7, the latter is tightly held in the position to which it was adjusted for lengthening or shortening the prop upon releasing that member by unscrewing the handle. To apply my device to its primary clothes-line propping purpose, after adjusting the 110

members by the handle of the screw 15 to render the prop of the desired length, it is applied to the clothes-line by catching the latter in the clip 16. This affords the advantage over the usual V-shaped notch in the end of a clothes-line pole, of preventing accidental dislodgment from the notch of the line, which is liable to occur when the clothes are hung in the open air, as by being swayed by wind. My clip is sufficiently rigid to hold the line in it against such accidental withdrawal, whereas if released from the line the latter would sag and lower the clothes hung on it to the ground with resultant soiling.

I realize that considerable variation is possible in the details of construction herein shown and described, and I do not intend to limit my invention thereto except as pointed out in the appended claim, in which it is my intention to claim all the novelty inher-

ent in my invention as broadly as permissible by the state of the art.

I claim:

A clothes-line prop having a pair of members connected by spaced loops to be relatively adjusted longitudinally, one of said members containing a threaded opening, handle-equipped means for releasably securing said members in adjusted position, said means comprising a block extending through a pair of said loops to bear against the outer face of said member and containing a threaded opening to register with said first-named opening, and a grip-handle for manipulating the prop in placing it into and removing it from operative position, said handle being provided with a screw-thread working through said block-opening and in the opening in said member against the opposing face of the outer member.

JAMES W. DAWSON.
